D. CLERICO

VALVE SPRING LIFTER FOR AUTOMOBILE AND OTHER ENGINES

Filed Jan. 27, 1922

INVENTOR
Dominick Clerico
BY Chas. C. Bell
ATTORNEY

UNITED STATES PATENT OFFICE.

DOMINICK CLERICIO, OF YONKERS, NEW YORK.

VALVE-SPRING LIFTER FOR AUTOMOBILE AND OTHER ENGINES.

Application filed January 27, 1922. Serial No. 532,064.

To all whom it may concern:

Be it known that I, DOMINICK CLERICIO, a citizen of the United States, and a resident of Yonkers, in the county of Westchester and State of New York, have invented certain new and useful Improvements in Valve-Spring Lifters for Automobile and Other Engines, of which the following is a specification.

10 The invention resides in a tool of novel construction for use in compressing the valve-springs of internal combustion engines preparatory to the removal of the valves, and one object of the invention is to provide a tool of the class referred to which shall have a wide range of adaptability to engines varying in size and formation and be capable of use in compressing the valve springs thereof on the exercise of a minimum 20 degree of force on the part of the operator. A further purpose of the invention is to provide a tool of the class referred to which may be very conveniently and quickly operated and used on valves regarded as more or less 25 inaccessible to the usual commercial types of valve spring lifters or compressors. A further object of the invention is to provide a valve spring tool of very durable construction and composed of a few parts lacking in 30 complexity and formed mainly of forged metal bars pivoted together and affording jaw members to engage the valve and its spring and handle members so pivoted together and to the jaw members as to render 35 it entirely convenient to on the movement of the handle members toward each other, cause the jaw members to approach each other and firmly compress the spring. The tool of my invention also provides means for 40 locking the jaws stationary when they are engaged in holding the valve spring compressed and for quickly releasing said jaws at the proper time so that the expansive force of said spring may automatically open 45 said jaws to free the same from the spring and valve.

The invention will be fully understood from the detailed description hereinafter presented, reference being had to the accompanying drawings, in which:

Fig. 1 is a side elevation of a valve spring compressing tool constructed in accordance

with and embodying my invention, the tool being shown in operative position holding a valve spring of an internal combustion engine under compression, a portion of the engine being shown in section;

Fig. 2 is a horizontal section, on a larger scale, through the same, taken on the dotted line 2—2 of Fig. 1;

Fig. 3 is a vertical transverse section, partly broken away, through the same, taken on the dotted line 3—3 of Fig. 2;

Fig. 4 is a vertical transverse section, on a larger scale, through the same, taken on the dotted line 4—4 of Fig. 2;

Fig. 5 is a detail sectional view of a portion of the same, taken on the dotted line 5—5 of Fig. 1, and

Fig. 6 is a side view of a modified form of jaw-member.

In the drawings, 10, 11, respectively, designate the upper and lower main jaw members of the tool and 12, 13, respectively, the handles or operative members by which the jaws 10, 11 may be moved toward and from each other. The upper jaw member 10 has a horizontal portion 14, an inwardly extending right angular portion or approximately vertical member 15 and a downwardly and rearwardly inclined member 16 projecting from the lower end of the member 15, said members 14, 15, 16 being formed from one integral flat bar of metal.

The opposite or, as shown, lower jaw member 11, has an inwardly extending or approximately vertical right angle member 17 and an upwardly and rearwardly inclined member 18 projecting from the inner end of said member 17. The members 16, 18 of the main jaws converge rearwardly toward each other and lie on opposed equal angles and constitute lever arms whose motion is transmitted to and accentuated in the main jaws 10, 11, whereby said jaws on a limited movement of said lever arms are caused to have an extended or wide range of movement toward and from each other. The handle bar 12 is pivotally connected with the member 16 by a pivot 19 and is also, at its inner or forward end, connected by a pivot 20 with the inner end of the handle bar 13. The handle bar 13 is secured by a pivot 21 to the jaw member 18, and, as aforesaid, is con-

nected by the pivot 20 with the handle bar 12. The converging members 16, 18 are connected together at their rear ends by a pivot 22, and, as shown in Fig. 2, the pivots 19, 21 are at intermediate points in the length of the members 16, 18 and disposed in a plane centrally between the pivots 20, 22.

Upon the handle bar 13 is secured, by a pivot 23, a segmental rack 24 having at its shank end a thumb-piece 25 and at its other end being connected by a spring 26 with the member 16 of the jaw 10. Upon the handle bar 12 is secured a loop 27 through which the rack 24 may loosely pass and whose forward inner edge serves as a pawl to engage the teeth of the rack to prevent the separation of the handles 12, 13 and jaws 10, 11, except when by pressure applied on the thumb-piece 25 the rack is swung outwardly free of the forward end of said loop 27 and in opposition to the force of the spring 26, which normally acts to press the rack 24 against the forward end of said loop.

The handles 12, 13 normally diverge rearwardly from their forward pivoted-together ends, as shown in Fig. 1, and by preference these handles will be constructed of steel in the form of flat bars and be furnished at their outer ends with wooden hand-pieces 30 or facings 28.

The upper jaw 10 has secured to the forward end of its horizontal member 14 a head-piece formed with an internally threaded bore 30 to receive the vertical screw 31 carrying at its outer end finger pieces 32 and at its inner end a pressure disk 33 whose upper portion is formed with a socket for a ball 34 formed on the lower end of the screw 31, said socket and said ball constituting a ball-and-socket joint adapting the disk 33 to yield to irregularities of the valves with which it may be placed into contact. I illustrate the disk 33 as being in engagement with the top of a valve 35 of an engine 36. The screw 31 permits of the adjustment of the disk 33 with respect to the engine parts, and in Fig. 1 the screw 31 is shown as having been entered into the valve-casing of the engine so as to carry the disk 33 against the upper surface of the valve 35. The valve 35 is upon the upper end of the usual valve stem 37 and is normally held on its seat by means of a strong coiled spring 38 which, as usual, is restrained between a washer 39 and a pin 40, the latter being removable from the valve stem after the pressure of the spring 38 has been released from said pin. The engine parts shown are merely illustrated and constitute no portion of the present invention.

The main jaw member 11 comprises a forwardly bent arm 41 integral with the member 17 and two bar members 42, 43 whose rear ends are riveted to the said mem-

ber 41 at opposite faces thereof and which members diverge forwardly from each other at equal angles and at their forward ends are bent outwardly in opposite directions from each other, as at 44, and thence extend forwardly on substantially parallel lines, as at 45, the portions 45 being of reduced vertical height, as shown in Fig. 1, and having at their lower edges inwardly turned flanges 46 to afford seats for the lower end of the spring 38, as shown in Fig. 2, a washer 47 usually being provided at the lower end of said spring, as illustrated in Figs. 2 and 3.

The members 42, 43 of the lower jaw 11 are capable of adjustment at their forward ends toward and from each other so as to adapt the tool for springs 38 and valve stems 37 varying in diameter and other characteristics, and as means for adjusting the members 42, 43 and holding the same in such adjustment, I provide the screw 48 which engages a threaded hole 49 in the member 43 and has a reduced end or threaded stem 50 extending freely through a hole 51 in the member 42. Upon the stem 50 is applied a hemispherical washer 52 and a nut 53, the washer 52 being provided to seat against the rounded outer edges of the hole 51 and the nut 53 being utilized to engage the washer 52 and hold the same in position. The arcuate side of the washer 52, with the free hole 51 and stem 50, permits of the adjustment of the jaw members 42, 43 toward and from each other in an effective manner. The screw 48 will be equipped with finger-holds 54 permitting it to be adjusted or turned by hand, and at the outer end of its body portion said screw is rounded and abuts against the bar member 42 at the hole 51, as shown in Fig. 4.

The purpose of the adjustment of the forward ends of the jaw-members 42, 43 toward and from each other, is to adapt the tool, at the portions 45, 46 thereof, for handling springs 38 of the varying diameters at present employed on the valve stems of internal combustion engines. The jaw-members 42, 43 constitute a fork adapted at its forward end to straddle the spring 38 and permit the flanges or seats 46 to be forced between the washer 47 and cotter pin 40 at the lower end of said spring.

The forward convergence of the handle-bars 12, 13 and the rearward convergence of the members 16, 18 of the jaws 10, 11, with the manner shown of pivotally connecting said parts, results in the jaws 10, 11 being moved inwardly or closed toward each other when the rear portions of the bars 12, 13 are pressed toward each other and in said jaws 10, 11 opening outwardly when the outer portions of the bars 12, 13 are turned outwardly or in a direction from each other. The forward portion of the handle-bar 12

is parallel with the inclined member 18 of the lower jaw 11, and the forward portion of the handle-bar 13 lies parallel with the inclined member 16 of the upper jaw 10, and this arrangement of the handle-bars and jaw members results in the operator being enabled, by the leverage thereby created, in securing maximum effect in the action of the jaws on the spring 38 with the application of minimum force to the handle-bars 12, 13.

In the employment of the tool, the handles are first opened outwardly and the seats 46 are forced between the washer 47 and cotter pin 40 and the screw 31 is lowered through the valve-opening in the engine casting to carry the disk 33 against the valve 35, and thereupon the handles are pressed in a direction toward each other to act against the jaws 10, 11, with the result that the disk 33 is pressed firmly against the valve 35 and the jaw 11 compresses the spring 38 upwardly against the bushing 39, leaving the pin 40 free to be removed. After the pin 40 has been removed, the spring 38 is allowed to expand and the tool is removed from the engine, whereupon the valve 35 may be withdrawn for such attention as it may require. After the valve 35 has been restored to the engine, the tool may be employed for compressing the spring 38 preparatory to the replacement of the cotter pin 40 and then again withdrawn to allow the spring to expand against said pin.

In the assembly of the parts of the tool I prefer to arrange the jaw member 16 and forward portion of the handle-bar 13 on the same vertical plane, and the jaw member 18 and forward portion of the handle bar 12 on the same vertical plane, thereby equalizing the strains through the tool and producing an efficient construction.

In Fig. 6 I illustrate a modified shape of lower jaw-member, this new shape having an upward bend, as at 60, to enable it to reach certain locations in which the straight jaw members shown in Fig. 1 might not be appropriate.

The jaw-members 42, 43 are secured together and against a spacing block 61 by rivets 62, and the rear ends of said jaw-members form a fork which straddles the forward end of the bar portion 41 and are removably secured thereto by bolts 63. The bolts 63 render the jaw-members 42, 43 detachable from the bar-member 41, and this is important in permitting me to substitute different shapes of jaw-members in the tool for the special shaped members shown, thus giving the tool a more universal range of usefulness. The jaw-members 42, 43 may be handled as a unit, and hence it is entirely convenient to apply them to the lower forwardly projecting bar portion 41, and the jaw-members 42, 43 are prevented from

swiveling action due to the bolts 63 and the flat contacting surfaces of the block 61 and the end of the bar-member 41.

What I claim as my invention and desire to secure by Letters Patent, is:

1. A tool for compressing a valve spring comprising upper and lower jaws having inwardly extending portions and thence rearwardly converging members pivoted together at their rear ends, upper and lower handle bars whose forward portions converge and are pivoted together at their forward ends and which portions cross the said rearwardly converging members of said jaws and are pivoted thereto at corresponding points between the vertical planes of the pivot points at the forward end of said handle bars and rear end of said jaw members, and a manually releasable rack for holding the handle bars in their closed relation in opposition to the force of the valve spring, the forward end of the upper jaw having means for engaging the top of the valve, and the forward end of the lower jaw having seats to pass below the valve spring and compress said spring when the handle bars are pressed in a direction toward each other.

2. A tool for compressing a valve spring comprising upper and lower jaws having inwardly extending portions and thence rearwardly converging members pivoted together at their rear ends, upper and lower handle bars whose forward portions converge and are pivoted together at their forward ends and which portions cross the said rearwardly converging members of said jaws and are pivoted thereto at corresponding points between the vertical planes of the pivot points at the forward end of said handle bars and rear end of said jaw members, and a manually releasable rack for holding the handle bars in their closed relation in opposition to the force of the valve spring, the forward end of the upper jaw having means for engaging the top of the valve, and the forward end of the lower jaw having seats to pass below the valve spring and compress said spring when the handle bars are pressed in a direction toward each other.

3. A tool for compressing a valve spring comprising upper and lower jaw members

130

connected together and having means for pressing them in a direction toward each other for compressing the spring, the upper jaw member having on its forward end 5 means to engage the top of the valve and the lower jaw member comprising oppositely disposed spaced apart bars adapted to straddle the valve spring and having seats to pass below said spring for compressing the 10 same and means for setting said bars in adjusted relation to each other, whereby to adapt the tool for springs varying in diameter, and said means consisting of a manually operative screw engaging a threaded 15 hole in one of said bars and having a reduced threaded end passing freely through a hole in the other bar against which the body of the screw abuts, a washer on said reduced end engaging the outer face of said other bar 20 and a nut on said end engaging said washer.

4. A tool for compressing a valve spring comprising upper and lower jaws having inwardly extending portions and thence rearwardly converging members pivoted together at their rear ends, upper and lower handle bars whose forward portions converge and are pivoted together at their forward ends and which portions cross the said rearwardly converging members of said jaws 25 and are pivoted thereto at corresponding points between the vertical planes of the pivot points at the forward end of said handle bars and rear end of said jaw members, and a manually releasable rack for 30 holding the handle bars in their closed relation in opposition to the force of the valve spring, the rearwardly converging member of the upper jaw being parallel with and on

the vertical plane of the forwardly converging portion of the lower handle bar and the rearwardly converging member of the lower jaw being parallel with and on the vertical plane of the forwardly converging portion of the upper handle bar, the forward end of the upper jaw having means for engaging the top of the valve, and the forward end of the lower jaw having means to pass below the valve spring for compressing said spring when the handle bars are pressed in a direction toward each other. 40

5. A tool for compressing a valve spring comprising upper and lower jaws whose rear portions are pivoted together and whose forward portions are spaced apart and the lower one of which has a pair of jaw members removably secured thereto, these jaw members being adapted to straddle the valve stem and having lips to enter within the vertical outer plane of the valve spring, and upper and lower handle bars whose forward ends are pivoted together and cross rear portions of said upper and lower jaws and are pivotally secured thereto at points intermediate the forward ends of the handle bars and the rear ends of said jaws, said pair of jaw members being bars set on edge and near their rear portions spaced apart by and riveted to a spacing block, leaving the rear ends of said bars in the form of a fork straddling the main bar of the lower jaw and removably secured thereto by bolts. 45 50 55 60 65 70

Signed at New York city, in the county of New York and State of New York, this 24th day of January, A. D. 1922.

DOMINICK CLERICO.
